UNITED STATES PATENT OFFICE.

CHARLES E. FLANAGAN, OF STEUBENVILLE, OHIO, ASSIGNOR OF ONE-HALF TO ISAAC M. SCOTT, OF STEUBENVILLE, OHIO.

TELEMETER-ROD.

939,489.

Specification of Letters Patent.

Patented Nov. 9, 1909.

Application filed March 3, 1909. Serial No. 481,124.

To all whom it may concern:

Be it known that I, CHARLES E. FLANAGAN, a citizen of the United States of America, and resident of Steubenville, county of 5 Jefferson, and State of Ohio, have invented certain new and useful Improvements in Telemeter-Rods, of which the following is a specification.

This invention relates to a distance-computing device, and more particularly to a combined telemeter and leveling-rod.

The primary object of the invention is to provide a distance-measuring instrument adapted for surveyors' use by means of 15 which the rodman may, without mathematical computation, accurately read the distance between the point at which the instrument is located and the surveyor's transit.

20 A further object is to provide an extremely simple and inexpensive device of the character mentioned which may be used as an ordinary leveling-rod.

With these and other objects in view, the 25 invention finally consists in the particular construction, arrangement and combination of parts which will hereinafter be fully described, reference being had to the accompanying drawing, forming a part of this 30 specification, in which—

Figure 1 is a front elevation of the rod; Fig. 2 is an enlarged front elevation of a portion of said rod, showing the graduations thereon; Fig. 3 is a top plan view of said 35 rod, illustrating the folding feature thereof; Fig. 4 is a front elevation of a broken portion of the rod mounted on a tripod; Fig. 5 is a section on the line 5—5, Fig. 4; and— Fig. 6 is a section on the line 6—6, Fig. 2.

40 Referring to said drawing, in which like reference-characters distinguish like parts throughout the several views—1 indicates a rod which is preferably about ten feet in length and which, for convenience in handling when not in actual use, is composed of two sections hinged together at 2. Said rod is adapted to be mounted in horizontal position on a tripod 3, or other support, a spirit-level 4 being provided in the upper edge of 45 the rod for facilitating the leveling of the latter.

Rigidly mounted upon the upper and lower edges of the rod adjacent to one end thereof are plates 5 and 6 which project 50 rearward beyond the rear face of the rod, as

shown, each plate having a vertically-disposed terminal wing 7 provided with a narrow vertical slot or sight aperture 8, the purpose of which will presently be made apparent.

60 Mounted upon said rod in any appropriate manner is a slidable target 9 which, in the present instance, has a pair of oppositely-disposed tongues 10 for traveling in grooves 11 provided in the upper and lower edges of the rod. A spring-catch 12 is adapted for normally holding said target in initial position at the line 13 on said rod which represents zero in the readings.

70 The face of the rod has thereon three sets of graduations, that adjacent to the upper edge being a scale of rods divided into tenths and numbering from 0 to 320 (the latter number not shown), and that adjacent to the lower edge being a scale of feet divided 75 into tenths and numbering from 0 to 5280 (the latter number not shown). As is obvious, various other methods of graduating the rod may be employed, but that shown and described is deemed preferable and 80 serves to here illustrate the use of the device.

In practice, when the rodman plants his instrument at a distance from the transit, he levels the rod 1 and turns the same at direct right angles to the transitman's line of 85 vision, or until the slots 14 in the wings 15 of the target 9 register in the said line of vision with the slots 8 in the wings 7. The transitman sights the telescope of his transit at said slots, making note of the angle, 90 after which he turns his telescope five minutes to the right. The rodman then moves the target along the rod until the slots again appear directly in the transitman's line of vision through the telescope; then, using the 95 vernier markings on the beveled edge 16 of the upper horizontal member 9^a of the target, he reads directly from the rod the distance in rods between the transit and the rod 1, or target; or, using the vernier on the 100 beveled edge 17 of the lower horizontal member 9^b, he reads the distance in feet. The reading of distance between the transit and the target, indicated by the position of the target in Fig. 2, is 40 rods, or 660 feet. The 105 transitman may also readily determine the distance, and thereby keep an accurate check on the rodman's readings, in various ways, an illustration of one of which will suffice:

A sight is first taken at the zero mark 13 110

on the rod, then a second sight is taken at the "5280 foot" mark or line on the rod, said mark or line being indicated by the numeral 18 in Fig. 1 of the drawing. By 5 dividing the number 26400 by the number of minutes in the angle traversed in the movement of the transit telescope from the first to the second position, the distance in feet between the transit and the target will 10 be accurately determined.

As is obvious, the use of the tripod for supporting the rod 1 may be dispensed with in cases where an accurate vertical arc is provided on the transit, the rod 1 in such 15 case being held in a vertical position instead of a horizontal position.

The middle row or set of graduations on the face of the rod is a scale of feet divided into hundredths and readable to thousandths 20 of a foot, by means of the vernier markings on the beveled edge 19 of the middle horizontal member 9^c of the target, this set of graduations being employed as on an ordinary leveling-rod.

25 For causing the two sections of the rod to stand rigid when in extended position, the adjacent ends of the sections are undercut and caused to overlap, as shown, and a stud 20 carried by one section adjacent to 30 the end of the undercut portion thereof projects through an aperture 21 provided therefor in the other section, said stud having a pivoted cross-bar 22 thereon adapted to be turned into interlocking engagement with 35 the rear face of the last-mentioned section.

When the two sections of the rod are folded together, the section opposite to that which carries the plates 5 and 6 fits snugly in the pocket formed between the rearwardly 40 extended portions of said plates, and lateral displacement of said sections is thereby prevented.

While the tripod 3 may be of any appropriate construction adapted for supporting 45 the rod, that illustrated in Figs. 4 and 5 is preferred because of the relative simplicity of its rod-holding head, said head consisting of a substantially U-shaped spring-metal rod-receiving clamp 23 the opposite 50 members of which may be readily drawn into clamping engagement with the rod by manipulation of a thumb-nut 24 carried upon the threaded end of a bolt 25 passed vertically through said members.

55 From the foregoing it will be seen that I provide an extremely simple, inexpensive and efficient device of the character men-

tioned, by means of which civil engineers and others may readily and accurately determine distances without calculations of 60 any kind being rendered necessary.

Having thus described my invention, what I claim as new, and desire to secure by Letters Patent, is—

1. A telemeter rod consisting of a rod 65 having a plurality of sets of graduations in different units arranged longitudinally thereon, and a movable target having a plurality of horizontal members with vernier markings thereon registering with all of said sets 70 of graduations.

2. A telemeter rod consisting of a rod having a plurality of sets of graduations in different units arranged longitudinally thereon, and a target slidably mounted on said 75 rod and having vernier markings registering with all of said sets of graduations.

3. A telemeter rod consisting of a target pole having a plurality of sets of graduations in different units thereon, a plate fixed 80 upon said pole and having a sight-aperture therein, a target movably mounted upon said pole and having a sight-aperture therein adapted to be brought into register with the aperture in said plate and also having a plurality of sets of vernier markings adapted to 85 register with all of said sets of graduations.

4. A telemeter rod consisting of a rod having a plurality of sets of graduations in different units thereon, a fixed plate carried by 90 said rod, a movable target carried by said rod, indicating means carried by said target registering with all of said sets of graduations, said plate and said target having sight-apertures therein whereby said rod may be 95 accurately adjusted at right angles to a distant telescope's line of vision.

5. In a device of the character described, a rod composed of two hinged sections, a pair of metal plates carried by opposite sides of 100 one section and projecting outward therefrom to form a pocket for the reception of the other section when the rod is folded, integral wings having sight-apertures therein 105 standing at right angles to each of said plates, and a target slidably mounted on said rod.

In testimony whereof I affix my signature in presence of two subscribing witnesses.

CHARLES E. FLANAGAN.
